CRATING MACHINE

Horace D. Stevens, Akron, Ohio, assignor, by
mesne assignments, to The Firestone Tire &
Rubber Company, Akron, Ohio, a corporation of
Ohio

Application August 10, 1937, Serial No. 158,333

9 Claims. (Cl. 226—2)

This invention relates to crating machines, and more especially it relates to apparatus for mounting a succession of articles in a crate or container in laterally spaced relation to each other.

5 The invention is of primary utility for crating storage battery plates during the manufacture thereof. Such plates are made in pairs, and consist of grid-like lead plates, the apertures of which are filled with a paste of lead oxide. Said 10 paste subsequently is dried in suitable ovens provided for this purpose, the pasted plates being suspended, in laterally spaced relation, in open crates as the latter are conveyed through said ovens. The crating machine constituting the 15 subject matter of this invention preferably is positioned between the plate-pasting apparatus and the drying ovens, so that it may receive the plates directly from the pasting apparatus, mount the plates properly in crates, and then deliver the 20 filled crates to a suitable conveyor for carrying them through the drying ovens.

The chief objects of the invention are to provide improved apparatus for automatically racking pasted storage battery plates in crates; to 25 provide for mounting the plates in suspended position; to prevent pendulous movement of the plates as they are conveyed through the apparatus and suspended in the crates; and to provide for synchronizing the movement of the plates 30 and crates so that the latter will be completely and uniformly filled. Other objects will be manifest as the specification proceeds.

Of the accompanying drawings:

Figure 1 is a side elevation of a complete machine embodying the invention, in its preferred form, the work therein being indicated in broken lines;

Figure 2 is an end elevation thereof, on a larger scale, as viewed from the right of Figure 1;

40 Figure 3 is a sectional plan view, on a larger scale, on the line 3—3 of Figure 1;

Figure 4 is a fragmentary plan view, on a larger scale, of the left end of the apparatus shown in Figure 1, the same being the work-receiving end 45 of the machine, the adjacent end of a grid-pasting machine being indicated in broken lines.

Figure 5 is a section on the line 5—5 of Figure 4;

50 Figure 6 is a section on the line 6—6 of Figure 4;

Figure 7 is a detail side elevation, on a larger scale, of the upper part of the machine, at the delivery end thereof;

55 Figure 8 is a plan view of the structure shown in Figure 7;

Figure 9 is an enlarged sectional view on the line 9—9 of Figure 10 showing in detail the mechanism that places the pasted plates in a crate;

Figure 10 is a section on the line 10—10 of Figure 9;

Figure 11 is a section on the line 11—11 of Figure 9;

Figure 12 is a section, on a larger scale, on the line 12—12 of Figure 1;

Figure 13 is a section on the line 13—13 of Figure 7;

Figure 14 is a section on the line 14—14 of Figures 7 and 8;

Figure 15 is a section, on a larger scale, on the line 15—15 of Figure 2;

Figure 16 is a section, on a larger scale, on the line 16—16 of Figure 15; and

Figure 17 is a section similar to that shown in Figure 10 showing a different setting of the plate-conveying instrumentalities for pasted plates of 20 a different size, and showing a crate of modified construction.

Referring to the drawings, it will be seen that the improved crating machine comprises an open framework 10 that carries three chain conveyors 25 11, 12, and 13, of which conveyors 11 and 12 are horizontally disposed and parallel to each other, and conveyor 13 is obliquely disposed with relation to both of them. Conveyor 11 is constantly driven and has one of its ends disposed at the 30 work-receiving end of the machine, adjacent the delivery end of a grid pasting machine indicated in broken lines by the rollers 14, 14, so as to receive paste-coated battery plates 15, 15 in succession from the latter. The conveyor 12 supports a succession of crates 16, 16, and is intermittently driven so as to feed said crates to the 35 delivery end of the machine. The conveyor 13 is positioned intermediate the delivery end of conveyor 11 and the leading crate 16 and is constantly driven so as to take successive plates 15 from the delivery end of conveyor 11 and to deposit said plates, in orderly arrangement, in said leading crate 16. As is shown most clearly in Figures 10, 12, 13 and 14, each battery plate 15 is formed with laterally projecting ears at its 40 upper margin, and the conveyor 11 consists of a pair of parallel chains upon which said ears may rest, the conveyor thereby pendulously supporting the plates between the chains.

Each chain of the conveyor 11 is provided with a series of spaced apart lugs 18, 18, the lugs on one chain being transversely aligned with the lugs on the other chain. The lugs 18 are of triangular shape and are so positioned on the chain 55

as to project upwardly from the upper reach of the latter. The machine is arranged to handle battery plates of different widths, and to this end means is provided for positioning the chains of respective conveyors 11 and 13 different distances apart from each other. With respect to conveyor 11, such means comprises elongate plates 19, 19 that are mounted upon longitudinally extending portions of the frame 10, at opposite sides thereof, as is best shown in Figures 4, 12, and 13, said plates being secured to the latter by suitable bolts 20, 20 that extend through transversely disposed slots in said framework, to permit lateral adjustment of said plates. Secured to the under side 15 of each plate 19, adjacent the ends thereof nearest the work-receiving end of the machine, are respective brackets 21, 21 each formed with a female screw thread, the framework 10 being suitably cut away to accommodate said brackets. 20 Mounted upon the framework 10, at opposite sides thereof and in axial alignment with brackets 21 are respective brackets 22, 22. Journaled in the latter is a shaft 23 that has its intermediate region formed with right and left hand screw 25 threads 24, 24 that are threaded through the respective brackets 21. One end of shaft 23 is squared at 25 to receive a suitable crank (not shown) by which the shaft manually may be turned, the opposite end of the shaft being provided with a sprocket 26.

In like manner the respective plates 19 are provided, adjacent their opposite ends, with respective brackets 28 (Figure 13) that receive right and left hand screw threads 33, 33 formed on a shaft 31 that extends transversely of the machine and is journaled in brackets 32, 32 secured to the framework 10. One end of shaft 31 is squared at 33 to receive a suitable crank, the other end of the shaft being provided with a sprocket 34 that is connected by a sprocket chain 35 with sprocket 26 on shaft 23. The arrangement is such that the rotating of either shaft 23 or 31 will move the plates 19 laterally toward or away from each other, when the bolts 20 are loosened, said bolts when tightened retaining the plates fixedly in position.

The ends of the plates 19 that are at the work-receiving end of the machine carry respective journal brackets 37, and journaled in each of the latter is a stub shaft 38, the adjacent ends of the latter being provided with respective sprockets 39. The opposite end portions of the plates 19 carry respective journal brackets 40 (Figure 13), and mounted upon the framework 50 10, in axial alignment with each of the latter is a journal bracket 41. In each pair of brackets 40, 41 is journaled a shaft 42, the adjacent ends of which carry respective sprockets 43. The two sprocket chains that constitute the conveyor 11 are each carried by a sprocket 39 and a sprocket 43. The outer end of each shaft 42 is slidably mounted for axial movement in a sprocket 44 to which it is keyed so as to be driven thereby, said sprockets 44 being engaged in respective forked brackets 45 that are mounted upon the framework 10 and prevent axial movement of said sprockets. The arrangement permits the shafts 42 to be driven in all positions of lateral adjustment of the plates 19.

70 For driving shafts 42, the sprockets 44 thereon are connected, by respective sprocket chains 47, with sprockets 48, 48 mounted upon opposite ends of an upper counter-shaft 49 that is journaled in bearing brackets 50, 50 secured to an upright portion of framework 10, near the work-

75 delivery end thereof. Adjustable idler sprockets 51, 51 engaging the respective chains 47 are provided for maintaining the latter in taut condition. The upper countershaft 49 also carries a sprocket 52 that is connected by a sprocket chain 53 with a sprocket 54 mounted upon a lower countershaft 55, the latter being journaled in bearing brackets 56, 56 mounted upon framework 10 near the bottom thereof. An adjustable idler sprocket 57 keeps chain 53 in taut condition. 10 Also mounted upon countershaft 55 is a sprocket 58 connected by a sprocket chain 59 with a sprocket 60 on the drive shaft 61 of a gear reduction unit 62 mounted below the framework 10. Said unit 62 is direct-connected to a power 15 unit, specifically a motor 63, the latter being equipped with the usual magnetic brake 64. The arrangement is such that the motor drives countershaft 55 at a speed of 35 R. P. M. The countershaft 55 may also carry a sprocket 65 with 20 which the sprocket chain 59 alternatively is engageable for driving said countershaft at a speed of 70 R. P. M.

The conveyor 11 moves at greater speed than the pasting machine so that it is important that 25 the grid plates 15 be fully clear of the rolls 14 of said pasting machine before they are engaged by said conveyor 11. To this end guide plates 68, 68 (Figures 4 and 5) are positioned to hold the ears of the grids off the chains of conveyor 11 until such time as the grids are out of the nip of rolls 14. Lateral guides 69, 69 also are provided for centering the grids relatively of the conveyor. A pair of obliquely disposed fingers 70, 70 are mounted upon a transverse support 71 that is secured to framework 10, the free ends of said fingers being positioned adjacent the surface of lower roll 14 and adapted to support the trailing ends of plates 15 as the ears thereof are engaged by conveyor 11, thus preventing pendulous movement of said plates. Supported by the fingers 70, intermediate the same, is a rod 72 that extends obliquely downwardly with a gradual incline, said rod being so positioned as to engage in a medial notch in 40 the lower margin of the grid plates, so that as the grid plates are drawn longitudinally thereof they gradually assume a vertical position. Mounted upon the top of each adjustable plate 19 is a pair of angular brackets 74, 74, each pair 45 of which supports a rail 75 that is positioned beneath a chain of the conveyor 11 to prevent said chain from sagging. The friction of the chains of conveyor 11 is sufficient to draw the grid plates over the rod 72, the lugs 18 serving the 50 purpose of subsequently straightening the plates on the conveyor, if they are not properly positioned thereon, as presently will be explained.

The conveyor 12 which supports the crates 16 comprises a pair of transmission chains that are 55 provided at spaced points longitudinally thereof with lugs 77, 77, said lugs projecting upwardly on the upper reach of the chains and being adapted for driving engagement with the crates 16, the lugs on one chain being in transverse 60 alignment with the lugs on the other chain. The conveyor 12 is of sufficient length to receive several of the crates 16, the latter being manually placed thereon in end to end relation. The crate-loading region of conveyor 12 is disposed below conveyor 11, and at this end of the conveyor 12 the chains thereof are carried upon respective sprockets 78, 78 that are mounted upon a transverse shaft 79, the latter being journaled at its respective ends in bearing brack- 75

ets 80, 80 that are adjustably mounted upon framework 10 so that the chains may be maintained in taut condition. At the other end of conveyor 12, which is the delivery end thereof, the conveyor chains are carried upon respective sprockets 81, 81 that are keyed upon an intermittently operated drive shaft 82, the latter extending transversely of the machine and being journaled in bearing brackets 83, 83 (see Figure 2) carried by the framework 10. Between sprockets 78 and 81 the upper reaches of the conveyor chains are supported upon respective rails 84, which rails are carried by a series of transverse supporting rods 85, 85 that have their ends engaged in respective side plates 86, 86. The latter are carried by a plurality of angular, upstanding brackets 87, 87 that are supported by the framework 10, at opposite sides thereof. Said brackets also carry a pair of vertically adjustable, horizontally disposed, elongate plates 88, 88, which plates are disposed laterally each side of conveyor 12, a little above the chains thereof, and constitute a support and slideway for the crates 16 as the latter are propelled by the conveyor 12. The brackets 87 also carry a pair of guide rails 89, 89 that are positioned above the slide-plates 88 and somewhat laterally thereof, said guide rails effecting approximate centering of the crates 16 which are positioned between them.

It is important that the crates 16 be accurately positioned laterally while the grid plates 15 are being mounted therein. To this end the guide rails 89 have their inner margins somewhat cut away or recessed in the loading region, as is best shown at 91, 91, Figures 3 and 8, and other means provided for centering the crates in this region. Said other means comprises a pair of horizontal, parallel, guide-plates 92, 93 arranged on opposite sides of the course of the crates and so positioned that their adjacent margins engage opposite sides of the crates near the top thereof, one of said guide plates being yieldingly mounted and normally urged towards the other. The guide plate 92 is mounted upon the outer ends of a pair of spindles 94, 94 that are adjustably mounted in a pair of brackets 95, 95, the latter being integrally connected by an elongate angle-structure 96 that is secured to the frame 10. The guide plate 93 is mounted upon the outer ends of a pair of spindles 97, 97 that are slidably mounted in respective brackets 98, 98 that are integrally connected by an angle structure 99 that is secured to framework 10. Compression springs 100 mounted upon spindles 97 between the guide plate 93 and brackets 98 normally urge said guide plate 93 toward guide plate 92, outward movement of spindles 97 being limited by suitable nuts on the rear ends thereof. The arrangement is such that the guide plates 92, 93 yieldingly maintain the crates 16 in proper position upon the conveyor 12, and they also serve as brakes to prevent movement of the crates relatively of the conveyor chains each time the latter are advanced.

The crates 15 are open, endless metal structures that are symmetrical in form. The bottom of each crate is formed with three transversely extending ribs 102, 102 which rest upon the slide-rails 88 so that friction between the latter and the crates is reduced to the minimum. The upper margin of the opposite sides of each crate is formed with a succession of uniformly spaced notches 103, 103, the notches on one side of the crate being aligned with the notches on the other side thereof. The said notches 103 receive the

respective ears formed on the upper corners of the grid plates 15. Mounted in the bottom of each crate and extending longitudinally thereof is a centrally positioned channel 104 that has its leg portions upwardly extended and formed with notches 105 that are in transverse alignment with the notches 103 in the top of the crate. Notches 105 receive the lower marginal portions of grid plates 15 that are mounted in the crates. By engaging said grid plates at top and bottom, pendulous movement thereof is prevented, and contact of adjacent plates is avoided. The notches 103, 105 are so disposed as to make a continuous, uniformly spaced succession throughout a succession of crates that abut end to end, whereby the operation of loading the crates may be continuous. The bottom of each crate is notched or recessed at each end so as alternatively to receive two pairs of conveyor lugs 77 that propel the crate, the arrangement permitting the crates to be mounted upon the conveyor with either end foremost.

The chains of conveyor 12 intermittently are advanced a determinate distance by means actuated by the grid plates 15 as the latter are fed to the crate 16 in plate-receiving position, the distance traversed by each advancing move being the same as the distance between adjacent notches 103 and between notches 105. To this end one end of shaft 82 is extended laterally of framework 10 and provided thereupon with a ratchet disc 108. Journaled upon said projecting portion of shaft 82 is a lever comprising arms 109, 109 that are positioned on opposite sides of ratchet 108, and carry between them, at one end 30 thereof, a spring-pressed pawl 110 that is in engagement with the teeth of ratchet 108. Pivotally connected to the opposite end of lever-arms 109 is a pitman 111 that comprises a turnbuckle 112 by which the length thereof may be suitably adjusted. The other end of pitman 111 is pivotally connected to a crank pin 113 of a one-revolution clutch, Figures 15 and 16, which clutch comprises a body structure 114 that carries said crank pin, the latter being adjustable in said body by means of adjusting screw 115 to the end that the crank pin may be positioned at various degrees of eccentricity with relation to the axis of said clutch body. The clutch body 114 is journaled upon the adjacent end portion of constantly-driven shaft 55, and upon the end of the latter, interiorly of the clutch body, is mounted a one-tooth clutch disc 116. At one region the clutch body is slotted at 117 to expose the perimeter and tooth of disc 116, and mounted in said slot is a pawl 118 that is pivoted at its middle upon said clutch body. A compression spring 119 carried by the latter normally urges the nose of the pawl toward the disc 116. The opposite end of the pawl is disposed exteriorly of the clutch body, in position to be depressed, against the pressure of spring 119, to lift the pawl out of engagement with the tooth of disc 116.

Extending into the orbit of the outer end of pawl 118 is a hook-like finger 121 adapted to engage the said end of the pawl to depress the same and thereby to open the driving connection between the shaft 55 and clutch body 114, as is most clearly shown in Figure 15. A tension spring 122 connected to said finger and to a fixed point normally urges the finger toward this position. The finger 121 is mounted upon one end of a rock shaft 123 that also carries a lever 124, Figures 2 and 3, the latter having its free end 75

pivottally connected to the movable element of a solenoid 125. Operation of the latter is controlled by a switch 126, Figures 7 and 14, that is closed momentarily by means presently to be described. Actuation of the solenoid causes the clutch 114 to make one revolution, with the result that the lever 109 makes one oscillation and the ratchet 108 is moved angularly the distance of one tooth. This turns shaft 82 and advances the chains of conveyor 12 a distance equal to the space between adjacent notches 103 or 165 in the crates 16 on said conveyor. That end of shaft 82 that carries ratchet 108 also carries a handwheel 127 by which the shaft may be manually rotated, upon occasion, such as at the beginning of operation. The opposite end of shaft 82 carries a brake drum 128 that is engaged by a spring-drawn brake band 129, the arrangement preventing over-run of the shaft 20 as it is periodically indexed by the pawl and ratchet.

The conveyor 13 comprises a pair of parallel sprocket chains that are driven in the direction indicated by the arrows, and each chain carries spaced-apart pairs of fingers 131, 131 that project upwardly from the upper reach of the chains and downwardly from the lower reach thereof. The said fingers of one chain are transversely aligned with the fingers of the other chain, and the leading finger of each pair is pivotally mounted so that it may tilt rearwardly, the other finger of each pair being fixedly mounted on the chain. Associated with the conveyor 13 is a slideway consisting of a pair of parallel, oblique rails 132, 132 that are so positioned at the delivery end of conveyor 11 as to receive the pasted grid plates 15 therefrom, the lower ends of said rails being positioned adjacent to and above a crate 16 on conveyor 12. The slide rails 132 are supported by brackets 133 that are carried by the laterally adjustable plates 18 whereby said rails always are properly positioned with relation to the respective chains of conveyor 11. The grid plates 15 are suspended from the rails 132 by the ears at the upper corners of said plates, and the inclination of said rails is such that the grid plates require to be propelled therewith. The chains of conveyor 13 are so positioned that the fingers 131 on the lower reaches thereof will engage the grid plates to urge them along the rails 132, the plates being disposed between the fingers of each pair of the latter. The pivotal mounting of the leading finger of each pair enables it to tilt and thus to pass over a grid plate, so that the latter is engaged and propelled by the fixedly mounted trailing fingers, the leading fingers thereafter preventing the grid plates from sliding forward more than a limited distance. Since movement of the grid plates under the impetus of conveyor 11 stops as soon as said plates are deposited upon the slide rails 132, it follows that the plates will be properly positioned thereon for the reason that neither side of the plates will move down the slideway until impelled by the conveyor 65 chains 13.

At the upper end of the oblique conveyor 13, the chains thereof are trained about respective sprockets 135, 135, the hubs of which are keyed for axial movement upon an idler shaft 136 that is journaled in end-brackets 137, 137 mounted upon the upper part of framework 10 at opposite sides thereof. At the other end of conveyor 13 the chains thereof are mounted upon respective sprockets 138, 138 that are keyed for axial movement upon a driven shaft 139 that is journaled

in end brackets 140, 140 mounted upon framework 10 at opposite sides thereof. Intermediate the sprockets 135, 138, the lower reach of the conveyor chain passes under respective idler sprockets 141, 141 that are keyed for axial movement upon a shaft 142 that is journaled in bearing brackets 143 that are mounted upon a transversely extending member of the framework 10. For driving shaft 139, a gear 144, Figure 2, is mounted upon one end thereof, which gear is 10 meshed with a gear 144a mounted upon the upper countershaft 49.

The respective sprockets 135, 138, and 141 of each pair of said sprockets are arranged to be moved toward and away from each other to vary 15 the distance between the chains of conveyor 13 and thereby adapt the latter for the conveying of grid plates 15 of different widths. To this end a shaft 145 is suitably journaled upon the framework 10 beside and parallel to the shaft 20 139, said shaft 145 being formed with a right hand and a left hand screw thread 146, 146 upon which are threaded respective forked shipper-arms 147, 147 that engage the hubs of the respective sprockets 135. One end of shaft 145 25 is squared at 148 to receive a hand-crank (not shown) by means of which the shaft may be manually rotated to effect lateral shifting of the sprockets 135. Similarly a shaft 150 is journaled on the framework 10 adjacent and parallel to the shaft 139, and formed with a right hand and left hand screw thread 151, 151 upon which are threaded respective forked shipper arms 152, 152 that engage the hubs of the respective sprockets 138. In like manner a shaft 153 is journaled on 30 the framework 10 above and adjacent shaft 145 and formed with a right hand and left hand screw thread 154, 154 upon which are threaded forked shipper arms 155, 155 that engage the hubs of the respective sprockets 141. The adjacent ends 40 of the shafts 145, 150, and 153, on one side of the machine (the near side as viewed in Figures 1 and 7 of the drawings) are provided with respective sprockets 157, 158, and 159, and trained about said sprockets is a sprocket chain 160. At 45 each side of sprocket 159 the chain 160 is engaged by adjustable idler sprockets 161, 161 for maintaining the chain in taut condition, and for providing a greater angle of engagement with said sprocket 159. The arrangement is such that 50 by manually rotating shaft 145 in one direction or the other, the respective conveyor chains of conveyor 13 may be moved from or toward each other.

As the grid plates 15 are moved downwardly 55 along the inclined rails 132 by the conveyor 13, their lower margins are engaged by a driven sprocket chain 164 that serves to prevent pendulous movement of the plates, said chain being driven substantially at the same speed as the 60 chains of conveyor 13. The lower margins of the plates engage the upper reach of said chain 164, which is downwardly inclined substantially parallel to said rails 132. The chain 164 is mounted upon a plurality of sprockets 165, 166, 165 65 167 and 168 respectively, said sprockets being arranged as is best shown in Figure 7. One sprocket, 165, alone is driven, the others being idlers. Sprocket 165 is mounted upon a shaft 169 that is journaled upon framework 10, said shaft carrying a gear 170 that is meshed with a gear 171 that is mounted upon a short shaft 172. The latter is journaled in a bearing bracket 173 that is carried upon framework 10, and has an end portion that projects from said bracket and car- 70 75

ries a sprocket 174 on said projecting portion. Sprocket 174 is connected by a sprocket chain 175 with a sprocket 176 mounted upon the driven shaft 142 of conveyor 13, the arrangement being such that chain 164 is driven at determinate speed with relation to the conveyor chains of conveyor 13.

At the lower end of each rail 132 is a hook-shaped terminal member 179 adapted to receive and support the successive grid plates 15, as they move off said rails, by engagement with the respective ears on said plates, the upper margin of each of said members 179 being more steeply sloped than the slope of the rails 132 so that as a grid plate moves onto said members it moves out of engagement with the fingers 131 of the conveyor chains 13 by dropping below the latter, as is most clearly shown in Figure 9 and Figure 11. The terminal members 179 are concurrently movable relatively of the rails 132 and a crate 16 for the purpose of depositing grid plates in the latter. To this end each terminal member is mounted upon the free, forward end of a lever 180 that is pivotally mounted at 181 upon an angular bracket 182 secured to one of the laterally adjustable plates 19. The rear ends of the levers 180 are pivotally connected to the lower ends of respective links 183 that are pivotally supported at their upper ends upon opposite end portions 30 of a cross-rod 184. The latter is carried by a lever 185 comprising three arms that engage said cross-rod at three points, said lever 185 being pivoted at 186 upon a pair of brackets 187, 187 on framework 10 that provide pivotal support for 35 two of the arms of the lever. At the opposite end of lever 185 from cross-rod 184 is carried a cam-roller 188 having operative engagement with a cam 189 on shaft 142, as is most clearly shown in Figure 13. The arrangement is such that the 40 rail-terminals 179 are depressed once during each revolution of shaft 142. The cam 189 is arranged on the shaft 142 so as to depress the rail-terminals 179 immediately after the chain-fingers 131 have deposited a grid-plate 15 thereon. To this 45 end the number of teeth on sprockets 141 on shaft 142 is the same as the number of links in each conveyor chain 13 between adjacent pairs of fingers 131, so that each revolution of the shaft advances the chains 13 a sufficient distance 50 to deliver a plate 15 to the rail terminals 179.

Cooperating with each rail-terminal 179 is a grid-plate stop 192 that projects laterally in front of an ear on a grid plate when the latter rests upon said rail-terminal, as shown in Figures 9 55 and 11. The stop plate 192 is pivotally mounted at 193 on a supporting plate 194 carried by bracket 182, and has its rear end portion positioned beneath a projecting structure on the adjacent end of lever 180. The arrangement is such that the 60 grid-plate engaging ends of the plate stops 192 are elevated by the operation of levers 180 as the latter depress the rail terminals 179 to deposit a grid plate 15 in a crate 16. This permits the crate to be indexed or moved forwardly the distance of one notch 103 immediately after a grid plate has been deposited therein, said members 179 and 192 both being removed from in front of the last deposited grid plates at this time.

In order to maintain the grid-plates 15 in proper position as they move down the rails 132, a pair of rubber straps or bands 197, 197 are suspended above the inclined course of the grid-plates in position to make frictional contact with the upper margins thereof. At one end the brake straps 197 are secured to a bar 198, Figure 1, that

is fixed to the top of the framework 10, and at their other ends they are attached to a vertically reciprocable plate stop 199 positioned immediately above the loading position of the plates. The plate stop 199 is formed with a plurality of downwardly extending lugs 200, 200 that are adapted to engage the upper marginal portion of a grid-plate 15 as the latter slides onto the rail-terminals 179, so as accurately to position said grid plate. The plate stop 199 is supported upon the lower 10 end of a slide 201 that is mounted in a vertically arranged slideway 202 carried by the framework 10. For reciprocating slide 201, a chain 203 has one end connected thereto, the other end of said chain being connected to the free end of a rocker arm 204 that is mounted upon one end of a rock shaft 205, the latter being disposed longitudinally of the framework 10 and suitably journaled in bearing brackets thereon. At its opposite end the rock shaft 205 is provided with a 20 lever arm 206 that is disposed parallel to rocker arm 204, the free end of lever arm 206 being connected to the adjacent end of lever 185 through the agency of an adjustable link 207. The arrangement is such that the plate stop 199 rises 25 whenever the lever 185 is operated to depress the rail-terminals 179.

In addition to the grid-plate stops aforesaid which engage the upper marginal portion and the lateral ears of the grid-plates, another stop is 30 provided for engaging the bottom marginal portion of said plates. This stop comprises a bridge member 210 that spans the course of the crates 16, above the latter, said bridge member being supported upon the respective guide rails 89. 35 Supported by said bridge member is a downwardly extending arm 211, to the lower end of which is secured an elongate journal bracket 212 in which is journaled a rock shaft 213. The bracket 212 is somewhat downwardly inclined toward its forward end, and the rock shaft 213 projects a substantial distance beyond said forward end. Fixed to the front end of rock shaft 213 is a radially disposed finger or stop pin 214 that is disposed in vertical or in horizontal position, according to the angular position of the rock shaft. When the stop pin 214 is in vertical position, as most clearly shown in Figures 9 and 10, it will extend between a grid-plate 15 suspended from the rail terminals 179 and a grid-plate in front 40 of the latter, resting in the crate. The arrangement is such as to prevent pendulous movement of the grid-plate on the rail terminals, so that said plate does not strike against the grid-plate in the crate. 45

The stop pin 214 is turned from vertical position to a horizontal position, as indicated in broken lines in Figure 10, concurrently with the depressing of the rail-terminals 179 and the elevation of the plate stop 199, so as to be clear of 60 the last deposited grid-plate as the crate 16 is indexed forwardly. For so turning said stop pin, the rear end of rock shaft 213 is provided with a short radial arm 216 that constitutes a counterweight for turning rock shaft 213 so as to move 65 the pin 214 from horizontal back to vertical position. For turning the rock shaft so as to swing the pin from vertical to horizontal position, said counterweight 216 is connected to the lower end 70 of an encased Bowden cable 217, the latter extending upwardly through the apparatus and having its upper end connected to the free end of a normally horizontal lever arm 218. The latter has its opposite end pivotally mounted at 75 219, Figure 14, upon a bracket 220 that is secured

to and extends downwardly from a transversely extending portion of frame 10. At an intermediate region of its length the lever arm 218 rests upon the lever 185, forwardly of the fulcrum 5 of the latter, the arrangement being such that when cam 189 operates lever 185, the latter lifts the free end of lever arm 218 and thus causes stop pin 214 to swing from vertical to horizontal position. When the free end of lever arm 218 10 descends to normal position, counterweight 216 rotates rock shaft 213 to return the stop pin 214 to vertical position. A stud 221 projecting radially from said rock shaft is so positioned as to abut a portion of bracket 212 so as to limit angular movement of the rock shaft under the pull of cable 217.

The switch 126, that controls the operation of solenoid 125 is provided with an operating lever comprising an elongate rod 224, said rod being 20 supported by a wire hook 225 secured to the framework 10, the arrangement being such that when the rod is lifted it closes the switch and thereby effects operation of the solenoid. The rod 224 extends obliquely downwardly from the 25 switch 126 into the path of the grid-plates 15 as the latter move down the inclined rails 132, and is arranged to be lifted by one of said grid-plates to effect operation of the solenoid. The rod 224 is somewhat flexible so that it may be bent to proper 30 position so as to be lifted in proper timed relation to the depositing of the grid-plates in a crate 16. Preferably the rod 224 is lifted to effect a forward indexing of the crate immediately after the cam 189 has depressed the rail terminals 179 and elevated the plate stop 199, to deposit a grid-plate in the crate, and while said rail terminals and rail stop are still in their respective 35 depressed and elevated positions.

In the operation of the machine, the grid plates 40 15 are received, in succession, upon the chain conveyor 11, and conveyed by the latter to the upper ends of the inclined rails 132, upon which they are deposited in position to be engaged by the fingers 131 of conveyor 13. The latter 45 impels the grid plates down the inclined rails and deposits them upon rail terminals 179, against stop members 192, 200, and 214. The crates 16 are manually mounted upon the slideway plates 88, in engagement with the upstanding lugs 77 50 on the chains of conveyor 12, so as to be intermittently advanced by the latter in a course which carries them below the rail terminals 179. The crates 16 advance intermittently a distance 55 equal to the spaces between adjacent notches 103 therein, which advance movement is the result of a grid-plate on inclined rails 132 operating solenoid 125 through the agency of switch 126 and lever-rod 224 of the latter. Cam 189 on shaft 142 comes into operation immediately 60 prior to the advance movement of the crates for the purpose of depressing rail terminals 179 so as to deposit a grid-plate in a crate, and for moving the plate stops 192, 200, and 214 to positions whereat they do not obstruct the movement 65 of the last-deposited grid plate as the crate subsequently is advanced.

The operation is continuous and substantially 70 automatic, manual labor being required only for the purpose of mounting empty crates in the machine and for removing the filled crates therefrom. The machine effects economy of time and labor and achieves the other advantages set out in the foregoing statement of objects.

The modified embodiment of the apparatus 75 shown in Figure 17 comprises a crate 16a that

in most respects is similar to the crates 16, but which is adapted to receive grid-plates 15a that are wider than the grid plates 15. The bottom portion of the crate 16a is identical with crate 16 so that mechanism of conveyor 12 will accommodate either crate without adjustment. The upper marginal portion of crate 16a, which includes the notches 103, is wider than the corresponding portion of crate 16, so that guide plates 92, 93 require to be laterally adjusted 10 when crates 16a are used. Crate 16a also is provided with side cleats, such as shown at 227, to facilitate handling of the crate. Figure 17 also shows the laterally adjustable plate 19 and mechanism carried thereby in position to accommodate the wide grid-plates 15a. The sprocket 138 of conveyor 13 also is shown in laterally adjusted position.

Other modification may be resorted to without departing from the spirit of the invention or 20 the scope thereof as defined by the appended claims.

What is claimed is:

1. In a crating machine of the character described, the combination of a pair of spaced, parallel, inclined rails adapted pendulously to support articles by engagement with ears projecting laterally from the upper corners thereof, means engageable with said ears for moving said articles, in succession, along said rails to the lower 30 end thereof, means comprising an endless driven member engageable with the lower margin of the said articles, as they move along said rails, for preventing pendulous movement thereof, and means at the lower end of said rails for depositing said articles, in succession, in a crate positioned thereat.

2. In a crating machine of the character described, the combination of a pair of spaced, parallel, inclined rails adapted pendulously to support articles by engagement with ears projecting laterally from the upper corners thereof, means engageable with one face of each article to move the latter along said rails to the lower end thereof, a flexible strap frictionally engaging the 40 upper margin of the articles in opposition to said article-removing means for holding the articles in engagement with the latter, and means at the lower end of said rails for depositing the articles, in succession, in a crate positioned thereat. 50

3. A machine for mounting grid-plates in crates, said machine comprising a pair of spaced, parallel, inclined rails adapted pendulously to support grid-plates by engagement with ears projecting laterally from the upper corners 55 thereof, means engageable with said ears for moving the plates, in succession, along said rails to the lower end thereof, means moving with the plates and engaging the lower margin thereof for preventing pendulous movement of the 60 plates, and means frictionally engaging the upper margin of the plates and opposing the movement of translation of the plates for holding the plates in engagement with the plate-moving means. 65

4. A machine for mounting grid plates in crates, said machine comprising a pair of spaced, parallel, inclined rails adapted pendulously to support grid-plates by engagement with ears projecting laterally from the upper corners 70 thereof, respective driven conveyor sprocket chains each having a reach disposed above and parallel to said rails, said chains carrying spaced fingers engageable with grid-plates on the rails for moving said grid-plates, in succession, to the 75

- lower end of said rails, terminal portions at the lower ends of said rails for receiving and supporting grid-plates in a position below the path of the conveyor fingers, and means for depressing said rail terminals in timed relation to the arrival of successive grid-plates thereon, so as to deposit the latter in a crate therebeneath, said means comprising a series of levers connected to the rail terminals, and a cam on a rotatable member of the conveyor for operating said levers.
- 5 10 15 20 25 30 35
5. A combination as defined in claim 4 including a rotatable shaft carrying the cam that operates the rail terminals and a pair of sprockets that engage the conveyor chains, each sprocket having the same number of teeth as there are links in the respective sprocket chains between adjacent fingers thereon.
6. A combination as defined in claim 4 including stop mechanism for accurately positioning a grid plate on the rail terminals, said stop mechanism being operatively connected to the cam and lever mechanism so as to move out of obstructing relation to the grid plate when the rail-terminals are depressed.
7. A machine for mounting grid-plates in a crate having an open top and ends, said machine comprising means supporting the crate and periodically effecting longitudinal movement thereof, means for pendulously supporting a succession of grid plates in vertical laterally spaced apart position above a crate, means for imparting an oblique downward movement of translation to the plates, transversely with relation to the plane of the plates and longitudinally with relation to the crate, said means being in such

proximity to the crate-supporting means as to position the plates within but out of engagement with the crate, and means for releasing the grid plates so that they drop vertically into engagement with the crate.

8. A combination as defined in claim 7 including means within the crate positionable between the last-deposited grid plate therein and the succeeding grid plate, and adapted to engage the lower extremity of the latter for preventing pendulous movement of the grid before it is released.

9. A machine for mounting grid plates in a crate having open top and ends, said machine comprising means supporting the crate and periodically effecting longitudinal movement thereof, means for supporting a succession of grid plates in vertical position above a crate, means for imparting an oblique downward movement of translation to the plates, transversely with relation to the plane of the plates and longitudinally with relation to the crate, said means being in such proximity to the crate-supporting means as to position the plates within but out of engagement with the crate, means for releasing the grid plates so that they drop vertically into engagement with the crate, a stop pin positioned within the crate and engaging the lower extremity of a grid plate therein to prevent pendulous movement of the plate before it is released, and means for moving the stop pin out of engagement with the grid plate concurrently with the release thereof.

HORACE D. STEVENS. 35
